US0D1072022S

(12) **United States Design Patent** (10) Patent No.: **US D1,072,022 S**
(45) Date of Patent: ** Apr. 22, 2025

(54) **PTZ CAMERA**

(71) Applicant: **Hangzhou Denghong Technology Co., Ltd.**, Hangzhou (CN)

(72) Inventor: **Jiayin Song**, Hangzhou (CN)

(73) Assignee: **Hangzhou Denghong Technology Co., Ltd.**, Hangzhou (CN)

(**) Term: **15 Years**

(21) Appl. No.: **35/518,636**

(22) Filed: **Sep. 28, 2023**

(80) **Hague Agreement Data**

Int. Filing Date: **Sep. 28, 2023**

Int. Reg. No.: **DM/231962**

Int. Reg. Date: **Sep. 28, 2023**

Int. Reg. Pub. Date: **Oct. 13, 2023**

(30) **Foreign Application Priority Data**

Sep. 12, 2023 (CN) 202330592837.X

(51) **LOC (15) Cl.** **16-01**

(52) **U.S. Cl.**

USPC **D16/203**
